(57) **CLAIM**

The ornamental design for a fitting, as shown and described.

DESCRIPTION

FIG. 1 is a top perspective view of a fitting, showing our new design;

FIG. 2 is a top view thereof;

FIG. 3 is a side view thereof;

FIG. 4 is a front side view thereof; and,

FIG. 5 is a cross-sectional view thereof, taken along section line V-V of FIG. 4.

The alternating dashed-line and solid-line pattern shown in the sectional view of FIG. 5 is only included to indicate sectioned portions of the fitting, and forms no part of the claimed design.
